(57) CLAIM

I claim the ornamental design for the inflatable toy hammer, as shown and described.

DESCRIPTION

FIG. 1 is a perspective view of the inflatable toy hammer of my new design;

FIG. 2 is a rear view thereof;

FIG. 3 is a front view thereof;

FIG. 4 is a left side view thereof,

FIG. 5 is a right side view thereof;

FIG. 6 is a top view thereof; and,

FIG. 7 is a bottom view thereof.

The broken lines represent portions of the design that form no part of the claim.
